By ~~William H. Hall, Atty.~~

UNITED STATES PATENT OFFICE.

HERBERT E. WALKER, OF CHICAGO, ILLINOIS.

DESIGN FOR A COMBINATION CONNECTOR FOR STORAGE BATTERIES.

60,279.

Specification for Design.

Patented Jan. 17, 1922.

Application filed April 6, 1921. Serial No. 459,154. Term of patent 7 years.

To all whom it may concern:

Be it known that I, HERBERT E. WALKER, a citizen of the United States, residing at Chicago, in the county of Cook and State of Illinois, have invented a new, original, and ornamental Design for a Combination Connector for Storage Batteries, of which the following is a specification, reference being had to the accompanying drawings, forming a part thereof.

Figure 1 is a plan view of a combination connector for storage batteries, showing my new design.

Figures 2 and 3 are side and end views, respectively thereof.

I claim:

The ornamental design for a combination connector for storage batteries, as shown.

HERBERT E. WALKER.
